UNITED STATES PATENT OFFICE.

PERCY J. HINDMARSH, OF LINCOLN, NEBRASKA.

FENCEPOST.

1,359,891.

Specification of Letters Patent. Patented Nov. 23, 1920.

Application filed September 23, 1919. Serial No. 325,804.

To all whom it may concern:

Be it known that I, PERCY J. HINDMARSH, a citizen of the United States, residing at Lincoln, in the county of Lancaster, State 5 of Nebraska, have invented new and useful Improvements in Fenceposts, of which the following is a specification, reference being had therein to the accompanying drawing.

Line fence posts for wire fences are made 10 of rolled steel T-shaped in cross-section the face and rib being made of the same thickness, which is about three-sixteenths of an inch. As the price at which they sell controls the weight of metal used in the 15 post, the face of the post (corresponding to the head of the T), is so narrow that the post cannot stand up unless to the part below ground an extra piece or plate is riveted to give the width necessary to the stability of the post. The object of my invention is to make unnecessary the use of this 20 additional plate, which adds to the cost, without adding to the weight of the post, to give it the required face bearing in the 25 ground that it must have to assure its stability.

In the annexed drawing:

Figure 1 is a perspective view of a fence post made in accordance with my invention; 30 and

Fig. 2 is a horizontal section thereof.

In the drawing, 10 designates the face of a T-fence post and 11 the rib thereof. The rib is of the standard or usual width and 35 thickness, namely one and one-half inches by about three-sixteenths. I have found that by rolling the face to reduce the thickness from about three-sixteenths to three-thirty-seconds of an inch, the face can be 40 widened to an extent that will assure the post all required stability when planted in

the ground, and with no addition of metal whatever, and without any impairment of its strength in the direction in which its strength should be greatest according to accepted practice, which is at right angles to the fence line. My post therefore, has the structural characteristic of the face member of less thickness and greater width than the rib. 45

For supporting the wires, I punch vertical tongues or hooks 13 at spaced intervals, alternate ones of which, vertically have their open ends up and down so that, adjacent strands 14 of woven wire will catch oppositely turned hooks, and thus, whether the fence goes down or up hill, the wires cannot pull out of the hooks. 50

I claim:

1. A fence post of T-cross section of rolled 60 metal having its face of greater width and less thickness than its rib or shank, the post being of the same cross section throughout substantially its length, the total weight of metal being the same substantially as if 65 face and rib were of like width and thickness, the surface of the face opposite the rib being crossed by the fence wire.

2. A fence post of T-cross section of rolled metal having its face of greater width 70 and less thickness than its rib, or shank, the post being of the same cross section throughout substantially its length, the total weight of metal being substantially the same as if face and rib were of like width and 75 thickness, the surface of the face opposite the rib being crossed by the fence wire, said face having spaced wire-engaging hooks in different vertical planes, opening respectively, up and down. 80

In testimony whereof I affix my signature.
PERCY J. HINDMARSH.
